UNITED STATES PATENT OFFICE.

HARRY LEVY, OF SOUTH PORTLAND, MAINE, ASSIGNOR TO THE NEW ENGLAND GUILD, OF PORTLAND, MAINE, A CORPORATION.

MACHINE FOR HOOKING RUGS AND THE LIKE.

Application filed December 11, 1925. Serial No. 74,789.

My invention relates to a machine used in the manufacture of hooked rugs, so-called, and which may be utilized on other work of a somewhat similar nature where 5 a loop stitch is employed.

The primary object of my invention is to construct a portable, power-operated machine capable of reeving yarn, rags or thread through a sheet, preferably burlap, 10 and forming thereon loops which are closely drawn against the sheet on one of the sides thereof and extending for a considerable distance outwardly from the other side,—these longer loops being subsequently cut 15 off in another operation in the process of manufacturing the rug.

Another object is to supply means to vary the length of these longer loops to obtain different thicknesses of rugs.

20 A further object relates to the simple but effective method of applying the power to the actuating parts whereby the starting and stopping of the machine may be accomplished with the least possible effort on the 25 part of the operator.

And a still further and very important object concerns the means employed to vary the relative positions of the needle and follower, so that each complete vertical stroke 30 of one may be made to act either in or out of synchronism with that of the other.

Other objects will be apparent after reading the specification especially when taken in connection with the accompanying drawings, in which like characters of reference 35 indicate similar parts throughout all the different views, and in which—

Fig. 1 is a front elevation of the rug hooker;

40 Fig. 2 is a sectional elevation thereof, taken on line 2—2, Fig. 1;

Figs. 3 and 4 are diagrammatical front and edge views, respectively, of the drive gears, showing one position of the cranks;

45 Figs. 5 and 6 are the same, except that the crank pins are shown in a different relative position.

Fig. 7 is a section on line 7—7, Fig. 2;

Fig. 8 is a section on line 8—8, Fig. 2;

50 Fig. 9 is a section through the male clutch member, similar to that shown in Fig. 2, but somewhat enlarged;

Figs. 10 and 11 are, respectively, the side and front elevations of a multiple needle;

55 Figs. 12 and 13 are, respectively, the side

and front elevations of a multiple follower;

Fig. 14 is a sectional elevation (fragmentary) of the needle and follower when in contacting position, and

Fig. 15 shows a fragmentary view of the 60 needle and follower, in section, mounted on a rug and in operative position,—this position corresponding to the crank positions illustrated in Fig. 6.

Referring to Figs. 1 and 2, 1 represents 65 the body of the machine which is preferably made of light metal, such as aluminum, for the purpose of greater ease in handling. A cored chamber 2 contains the drive elements. Covering openings out of each side 70 of the body member (1) are flanged bearings 3, the flanged portions of which, 3', are secured to the body member (1) by screws 4. Rotatable in these bearings, 75 which carry bushings 5, are shafts 6 and 7 having thrust collars 6' and 7', respectively, on their outer ends.

Fixed on the shafts 6 and 7 are gears 8 and 9, respectively, the former gear having a crank-pin 8' and the latter a crank-pin 80 9' projecting from their adjacent sides.

The lower front portion, 1', of the body 85 1 is made detachable, being divided as seen in Fig. 7. This is chiefly for the purpose of facilitating the assembling of the actuating parts within the body member. It will be observed that the configuration of the lower portion of the body is in the form of a handle which may be grasped by the operator while in the act of manipulating 90 the machine over the rug.

Within this handle the shank 10' of the needle 10 and the shank 11' of the follower 11, reciprocate. The shank 10' is pivotally connected at 12 with the connecting-rod 13, and the shank 11' has a similar connection at 14 with the connecting-rod 15.

Located interjacent and engaging both of the gears 8 and 9 is a pinion 16, fixed on the shaft 17. This shaft (17) is journalled in the bearing 18 within the cylindrical superstructure 19,—the latter being secured to the body member (1) by the screws 20. A collar 21, integral with the shaft 17, thrusts against one side of the bearing (18) and the hub of the pinion 16 acts in a corresponding capacity on the opposite end on the same bearing; thus the shaft 17 and pinion 16 are held against vertical movement in the body member 1. 110

On the extended portion of the shaft 17, above the collar 21, is the male portion of a friction clutch, 22, depending from which and integral therewith is a sleeve 22' and 5 surrounding this sleeve is the clutch collar 23, the latter being provided with an enlarged portion forming a shoulder, 23'. The sleeve and the male clutch element have axial movement on the shaft 17.

10 Encompassing the two flattened sides of the clutch collar 23 is the bifurcated arm or yoke 24 (see Fig. 8), the function of which is to raise the clutch collar and hold it against rotation. A ball thrust bearing is 15 interposed between the conical portion 22 and the clutch collar 23 (see Figs. 1 and 9); the yoke 24 thus also functions to lift the male clutch element 22 into engagement with the female clutch element 26. A feather, 20 or sliding key 25 operates to tie the male clutch member, with respect to rotation thereon, to the shaft 17, in which there is a key-way fitting the feather 25.

A collar 26' integral with the portion 25 26 bears on the uppermost end of the member 19 and interjacent the latter and the collared-sleeve 27 is the ball thrust bearing 28. A helical spring 28' keeps the male clutch part 22 normally separated from the 30 female element of the clutch, 26.

A cap 29 threaded on to the end of the cylinder element 19 holds the interposing parts from vertical movement other than what is necessary to provide free rotation 35 thereof.

The upwardly extending hub 30 of the female clutch element is bored to receive the end of the shaft 31 forming the rotative part of any suitable flexible shaft and 40 the two elements, 30 and 31 are secured together by the screw pin 32. This shaft (31) may be driven by any suitable prime mover and is the driving element for the hooking machine.

45 The flexible shaft casing 33 is secured to the sleeve 27 in any proper manner and these two elements, the sleeve and casing, are not rotatable. There is, however, provision for oscillating or turning the whole machine at 50 the joint marked *a*, this being necessary on account of the fact that in the hooking operation the machine needle must follow the delineations of the pattern stamped on the burlap base of the rug and consequently 55 must turn in whichever direction the lines are drawn.

The clutch yoke 24 is pivoted at 34 and on the outwardly projecting arm thereof is pivotally connected, at 35, one end of the link 36. 60 Also pivotally mounted on the detachable body portion 1', at 37, is the trigger 38, an off-set arm on which is pivotally connected to the opposite and lower end of the link 36. A slight pressure of the fore finger of 65 the operator on this trigger will throw the

male clutch element into engagement with the female clutch part and start actuation of the needle and follower.

By reference to Fig. 7 it will be observed that the shanks 10' and 11' of the needle and follower, respectively, reciprocate in a three-sided bushing 39 which is secured to the body 1 by the screws 40; and that on the forward side of the needle shank the screws 41 secure the plate 42 to the detachable portion of the handle 1'. 70 75

A hole 43 serves to guide and control the hooking material feeding from the supply reel (not shown) to the needle 10.

A foot 44 supports the hooking machine 80 as it travels over the rug and an aperture 45 admits the needle and follower to the work. This foot (44) has vertical adjustment on the body, a slot 46 therein permitting the same to slide over the clamping 85 screws 47. The detachable portion 1' of the handle is secured to the fixed portion 1 by the screws 47'.

In Fig. 1 I have illustrated the machine as a single needle rug-hooking device. In 90 Figs. 10 to 13 inclusive are portrayed how a plurality of needles and followers may be employed. Their application on plain one-color work or where there is extensive one-color background is especially profitable. 95 They also prove very effective where different colors alternate, as in striped designs of rugs.

In the process of rug making it is often 100 essential that the relative crank angles of the needle and follower be susceptible of change,—either directly and diametrically opposite or in closer approach to each other,—depending somewhat on the grade of hooking material being used.

Mainly to accomplish this object have I 105 resorted to the two-gear drive, and in Figs. 3 to 6 inclusive I have illustrated in diagrammatical form two different positions in which the crank-pins may be placed, the 110 Figs. 3 and 4 showing the latter diametrically opposite.

In Figs. 5 and 6 the follower crank-pin is shown considerably nearer the needle 115 crank-pin and in this instance the follower acts to hold the loop in place until the needle has just withdrawn from the rug. This is also shown in sectional detail in Fig. 15 where 48 represents the rug base or burlap and 49 the hooking material or filler used in the hooking operation. It will be noticed that the follower is at its lowest position and holds the loop intact during the slow movement of the crank about its lower center and that this position is properly timed to allow the needle to clear itself 125 from the rug.

To make any necessary change in the relative positions of the crank-pins I remove 130 the section 1' and the flanged bearing 3

which is adjacent the gear 8; this gear (8) may then be disengaged from the pinion 16, oscillated so that the correct crank angle is obtained and then re-engaged with the 5 pinion and the removed parts put back in their proper places.

When using heavy, coarse material for hooking and with the crank angles located as shown in Figs. 3 and 4, the needle will 10 tend to pull the loop back out of the rug base when on its upward stroke, before the follower has an opportunity to act. Cranks adjusted as seen in Figs. 5 and 6 eliminate this difficulty.

15 The employment of this steady crank action combined with the adoption of the friction clutch is a feature which is far superior to the usual or conventional type cam or spring actuated devices or positively locked clutches. The prominent characteristic of this drive is its ability to slip or yield when the needle encounters more than ordinary resistance in piercing the rug base. It also starts actuation of the parts much 20 more steadily and easily than a positively gripping clutch which takes hold with a jerking action which often breaks the yarn or other hooking material. Furthermore, the male, or driven member of the clutch is 25 supported on an anti-friction thrust which results in more power being delivered to the hooking elements. And lastly, it permits of the needle being operated at a much higher speed and this consequently tends to 30 greater production in manufactured goods.

While it does not, strictly speaking, function as a variable speed reduction device, my friction clutch combined with its associated elements does in actual practice 40 allow the operator unlimited opportunity to slacken the speed of the machine at critical times,—as when turning corners and following intricate designs in the pattern, and while the feed may be somewhat 45 spasmodic, it is easily and always under the control of the operator, who, by a light touch on the trigger may make the apparatus serve admirably for the purpose of which we speak.

50 In operation, the hooking material is first thereaded through the opening 43 and the eye of the needle 10; a slight pressure on the trigger 38 starts actuation of the needle and follower and a long loop will 55 form on the under side of the rug base and a short close one on the top. The lower loop may be varied in length by adjusting the foot 44, or by placing the crank-pins in other holes 50 in the gears, increasing or 60 decreasing the stroke of the needle and follower.

While the foregoing description and the 65 illustrations give a clear understanding of the preferred embodiment of my invention it is obvious that slight modifications in

the exact mechanical details herein disclosed might be desirable, and so it is to be understood that I shall feel at liberty to deviate in so far as such changes be kept strictly within the scope of the appended 70 claims.

What I claim and wish protected by Letters Patent is:

1. In a machine for hooking rugs and the like, comprising in combination a body member, a supporting leg depending from said body, a hooking needle reciprocable in and depending from said body member and adapted to operate through and for a spaced distance beyond said supporting leg, means 75 to vary by predetermined spaced distances the travel of said hooking needle beyond and below said supporting leg whereby various and predetermined lengths of loops may be had, a follower reciprocable in said body member and located in contiguous relation to said hooking needle and means to vary the relative positions of said hooking needle and said follower, longitudinally of their movements, whereby the hooking needle may 80 contact with the rug being hooked at various and predetermined spaced intervals preceding the contact of said follower with said rug.

2. In a machine for hooking rugs and the like, the combination, with a body member, a reciprocable hooking needle, a reciprocable follower and a supporting leg for said machine, of gears fixed on rotatable shafts disposed at right angles to said hooking needle and separated by a spaced distance, a pinion interjacent and engaging both of said gears, means to actuate said pinion, a crank-pin on each of said gears, a drive-rod connecting one of said crank-pins with said hooking 95 needle shank, a drive-rod connecting the other of the said crank-pins with the shank of the said follower and means to vary the stroke sequence of said hooking needle relative to that of said follower whereby the completion of the downward movement of said hooking needle may at predetermined times be made to precede that of the said follower by various and predetermined 100 spaced intervals, substantially as described.

3. In a machine for hooking rugs and the like, the combination, with a body member, a reciprocable hooking needle, and a reciprocable follower, of a female clutch member rotatably mounted in said body member, a male clutch member mounted in axial alignment with said female clutch member and separated a spaced distance therefrom, said female and male clutch members being 110 of the conventional friction type with 115 smooth face and bore and tapering, means to positively throw one of said clutch members into engagement with the other, means to yieldingly separate said clutch members, 120 means to actuate said female clutch member, 125 130

means interconnecting said needle and said follower whereby they may be actuated simultaneously, through the agency of said interconnecting elements, by said male clutch member when in engagement with said female clutch member, and means whereby said hooking needle and said follower may be located in relatively different positions through the transposition of said interconnecting elements whereby the reciprocations of said needle and said follower may be either in or out of synchronism, one with the other.

4. In a machine for hooking rugs and the like, the combination, with a body member, a reciprocable hooking needle, and a reciprocable follower, of a frictionally driven clutch embodying a male and female element, a sleeve depending from said male

bearing interjacent said male element and said collar, means to throw said male element into engagement with said female element, means to yieldingly disengage said male and female elements, a ball thrust bearing superimposed on said female element, whereby when the two said clutch elements are in engagement the thrust which holds them thus may be taken in two directions by ball thrust bearings, means to positively actuate said female clutch element, means interposed between said male clutch element and said hooking needle and said follower whereby the two latter members may be actuated simultaneously and means to make the reciprocations of said needle and said follower either synchronous or out of synchronism, substantially as described.

HARRY LEVY.
